[57] CLAIM

The ornamental design for a vacuum cleaner upper portion, as shown and described.

DESCRIPTION

FIG. 1 is a top, front and left perspective view of the vacuum cleaner upper portion showing my new design;

FIG. 2 is a front view thereof;

FIG. 3 is a left side view thereof;

FIG. 4 is a right side view thereof;

FIG. 5 is a rear view thereof;

FIG. 6 is a top view thereof;

FIG. 7 is an enlarged, partial top, front and right perspective view of the vacuum cleaner upper portion with the tool door removed; and,

FIG. 8 is a bottom plan view thereof.

The portion of the vacuum cleaner shown in broken lines in FIG. 1 is shown for illustrative purposes only and forms no part of the claimed design.
